UNITED STATES PATENT OFFICE.

HENRY O. LINDEMANN, OF TOMPKINSVILLE, NEW YORK.

DESIGN FOR A BIRD CAGE.

Application filed September 27, 1928. Serial No. 28,296. Term of patent 3½ years.

To all whom it may concern:

Be it known that I, HENRY O. LINDEMANN, a citizen of the United States, residing in Tompkinsville, in the county of Richmond and State of New York, have invented a new, original, and ornamental Design for Bird Cage, of which the following is a specification, reference being made to the accompany-

ing drawing, forming part thereof, in which: Fig. 1 represents a side elevation of a bird cage showing my new design.

Fig. 2 is a top view of the same.

I claim:

The ornamental design for a bird cage as shown.

HENRY O. LINDEMANN.
